UNITED STATES PATENT OFFICE.

OSCAR S. FOSTER, OF UTICA, NEW YORK.

SPRING-BED.

SPECIFICATION forming part of Letters Patent No. 496,404, dated May 2, 1893.

Application filed April 22, 1892. Serial No. 430,166. (No model.)

To all whom it may concern:

Be it known that I, OSCAR S. FOSTER, of Utica, in the county of Oneida and State of New York, have invented certain new and useful Improvements in Spring-Beds; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

My invention relates to an improvement in spring beds.

The object of my invention is to provide a spring bed that has its several parts of a shape to be easily and readily formed and having its several parts arranged to assemble easily, besides providing a bed that is compact, strong and uniformly elastic and yielding.

In the drawings which accompany and form part of this specification and in which similar letters and figures of reference refer to the same parts in the several views, Figure 1 shows a plan view of a portion of the bed. Fig. 2 shows a partial end view of the same, the bed slightly turned on its central hinge in the act of folding. Fig. 3 shows a clasp used in securing the stay wires or stay-wires and springs. Fig. 4 shows a spring without an arm in connection with the stay-wire and a clasp engaging the stay-wire and spring. Fig. 5 shows a spiral arm spring and in connection with stay or cross wires, and a clasp. Fig. 6 shows a complete double cone spiral arm spring, such as may be used in the bed in connection with stay wires and securing clasps.

The bed is composed of a number of double cone spiral springs as 1 and 2, preferably arranged in rows or courses each way across the face of the bed, the upper and lower convolutions of the several springs lying in the plane of, and forming in part the upper and lower faces of the bed respectively. The row of springs around the outside of each section of the bed are preferably arm springs 2 having an arm 2^a formed out of the same piece of wire as the spring and extending radially

therefrom in the plane of the end of the 50 spring and provided with a hook on its outer end.

The bed is composed of two sections as A and B. Each section is provided on the under side with border wire frame 3. The arms of the several border springs 2 engage the border frame 4. Longitudinally across the faces of the bed are provided bracing or stay wires 7 having their ends secured to the border row of arm springs by means of the clip herein-after described and by being twisted around the wire of the spring as shown at a, the wires 7 engage at the edges of the convolutions of the springs. Transversely across the faces of the bed are provided stay wires 10 which pass diametrically across the face convolutions of the springs and are secured on the opposite sides of the frame in the case of the upper face to the frame at 8 and to the central hinge wire 6 at 9. At the point where the longitudinal and transverse wires 7 and 10 cross is provided a clip or clasp 11. The clasp is formed in U or V shape and has a hole in each branch through which one of the wires is passed, the other stay wire being 65 previously placed within the space below the holes together with the convolution of the spring. The clasp is then pounded down flat, which bends the stay wire passing through the holes of the clasps at the point 70 where it engages spring and other cross wires. The wire that passes through the opening between the clasp and stay wire is provided with an off-set x of a width to receive the clasp and when the clasp is engaged therein, it 75 is prevented from moving or working along the wire.

Over the whole upper surface of the bed is provided a wire fabric, a portion of which is shown at F. The fabric is secured at its 80 edges by having the arms 2^a of the arm springs inserted through it and the fabric draws against the upper convolution of the spring as a shoulder.

What I claim as new, and desire to secure 85 by Letters Patent, is—

The combination in a spring bed having stay wires crossing each other substantially

at right angles and a spiral spring, of a clasp having perforations for receiving one of the stay wires and a bend between the perforations for receiving a convolution of the spring and the other stay wire, the last mentioned wire having an off-set at the point engaged by the clasp, substantially as set forth.

In witness whereof I have affixed my signature in presence of two witnesses.

OSCAR S. FOSTER.
